DESIGN FOR A PICTURE-CARRYING BROOCH OR THE LIKE

Max Fellman, New York, N. Y.

Application March 11, 1942, Serial No. 106,154

Term of patent 7 years

To all whom it may concern:

Be it known that I, Max Fellman, a citizen of the United States and residing at New York city, in the county of the Bronx and State of New York, have invented a new, original, and ornamental Design for a Picture-Carrying Brooch or the like, of which the following is a specification, reference being had to the accompanying drawing, forming part thereof.

Fig. 1 is a front view of a picture-carrying brooch or the like, showing my new design.

Fig. 2 is a side view thereof.

I claim:

The ornamental design for a picture-carrying brooch or the like, substantially as shown.

MAX FELLMAN.
